UNITED STATES PATENT OFFICE

JOHN H. MAGEE, OF CARTHAGE, MISSOURI

STRUCTURAL BUILDING UNIT

Application filed August 21, 1929. Serial No. 387,423.

This invention relates to structural building units.

The advantages to be gained by means of composite reinforced concrete building structures, and structures employing insulating material in conjunction with cement or other cementitious material and steel or other reinforcing material are well known. The provision of such a structure however has been carried out in a rather crude and inefficient manner at the place where the material is used, and the work has been done with high priced skilled labor which has added to the cost of the structures, out of proportion to the advantages gained, thereby limiting the usefulness of structures of the character referred to.

For example the advisability of using sheet cork, which is one of the best heat insulating materials known to the building industry, in connection with a steel reinforcing structure, is well understood in the building trades, but its use has been accomplished only with the greatest difficulty. Building cork, if loosely compressed to retain the highest possible heat insulating efficiency, possesses little or no structural strength, and accordingly is made up in relatively small pieces. In order to employ this material in connection with the building of walls, floors, partitions, etc., it is necessary to erect a supporting frame structure for the cork insulation, after which reinforcement is attached directly to the same or by some furring means. Plaster is then applied, and must be allowed to harden, after which the frame structure must be carefully removed. The operation is then repeated on the opposite side of the insulation. The whole operation is so tedious and expensive as to render the cost thereof prohibitive.

An important object of the present invention is to provide a building unit which may be completed at the factory, and shipped in relatively large sizes for use in forming walls, floors, roofs, partitions and the like wherein the unit is self-contained and self-supporting to a very great extent, and embodies the features of having heat and sound insulating means and metal reinforcing means therefor, and wherein the reinforcing

means serves the additional function of providing holding means for a layer or layers of cementitious material applied to one or both faces of the unit.

A further object is to provide a novel building unit of the character referred to which is adapted to be used in connection with cementitious material applied thereto whereby the finished structure will possess a high degree of tensile and compression strength, and which acts efficiently as a sound and heat insulating building structure.

A further object is to provide a building unit of the character referred to wherein the metallic reinforcing means serves to adequately protect the insulating material from injury during handling and transportation.

A further object is to provide a unit of the character referred to wherein the metallic reinforcing is so positioned with relation to the insulating material that the finished structure may embody a layer of cementitious material which substantially entirely surrounds the elements constituting the metallic reinforcement, thereby materially increasing the structural strength of the finished wall or other structure.

A further object is to provide a composite semi-completed building unit embodying a sheet or sheets of heat insulating material and a sheet or sheets of metallic reinforcing material, and to provide means connected to and between these sheets of material to secure the latter together as a unit and to utilize the reinforcing material as means for protecting the insulating material during handling and shipment and to bond with a sheet of cementitious material applied to the unit after the latter has been placed in desired position.

A further object is to provide a structure of the character referred to which is particularly adapted for use in connection with reinforcing means in the form of metallic reinforcement of the expanded metal type, and wherein the inherent characteristics of the reinforcement are employed for assisting in bonding the cementitious material to the metallic reinforcing means.

A further object is to provide a struc-

ture which embodies inherent characteristics which render it particularly adapted for use in connection with sheet cork as the heat insulating material whereby the advantages of such material may be used and wherein the usual disadvantage of such material because of its inherent structural weakness is of no importance.

5 A further object is to provide a building 10 unit which lends itself readily to use in the building of walls, hangars, floors, partitions and the like, and which is particularly adapted to be varied in its structure and arrangement of parts to increase its utility in connection with such various uses.

10 A further object is to provide a semi-finished composite unit embodying heat and sound insulating material and metallic reinforcing means of such nature that the adjacent 20 units used in constructing a wall or the like will be efficiently bonded together in the body of cementitious material applied thereto so as to impart to the finished wall or other structure substantially the same 25 structural strength as if the wall had been initially built as a single unit.

15 A further object is to provide a building structure wherein the metallic reinforcing means has substantially its entire body spaced 30 from the layer of insulating material so as to permit the metallic reinforcing means to be substantially entirely bonded in the body of cementitious material.

20 A further object is to provide a semi-finished structural unit adapted to be used for 35 forming reinforced concrete constructions without the use of insulating material, where the latter is of no importance, and to provide a structure which possesses a high degree of tensile and compression strength in proportion to the thickness of the finished structure.

35 Other objects and advantages of the invention will become apparent during the course 40 of the following description.

45 In the drawings I have shown several embodiments of the invention. In this showing,

50 Figure 1 is a side elevation of one of the units,

55 Figure 2 is a detail transverse sectional view showing the method of connecting two adjacent units,

Figure 3 is an enlarged fragmentary sectional view taken vertically through a portion of one of the units,

60 Figure 4 is a section similar to Figure 3 showing a modified form of the invention,

65 Figure 5 is a side elevation of a unit of the type illustrated in Figure 4,

Figure 6 is a section,

Figure 7 is a detail view similar to Figure 3 illustrating a further modification,

65 Figure 8 is a fragmentary side elevation of a modified form of the invention, and

Figure 9 is a detail sectional view of the same included in a finished structure.

Referring to Figures 1, 2 and 3, the numeral 10 designates a layer of heat insulating material of any suitable kind, such as natural 70 or manufactured wood, lumber, cork, or the like. As previously stated, the present invention is particularly adapted to employ cork as the heat insulating means, and the inherent structural weakness of such material is of no 75 importance. As will become apparent, the relatively small pieces of sheet cork which are commercially available are employed in end to end and edge to edge relation to make up an insulating unit of the proper size according 80 to the desired size of the completed structural unit being manufactured. The individual cork sheets are preferably staggered with relation to each other, as illustrated in Figure 1.

85 Metallic reinforcing means in the form of expanded metal 11 is employed adjacent opposite sides of the layer of insulating material, but it will become apparent that the metal may be employed at one side of the wall 90 if desired. It is preferred, however, that the metal be employed at both sides of the wall in view of the advantages to be gained thereby, such as greater inherent strength in the finished unit and structure, protection of the 95 layer of insulation during shipment, etc.

95 As is well known, the usual expanded metal is formed with a substantially diamond-shaped mesh, and comprises angular strands 100 12 defining the diamonds and connected by solid bridges 13. Both the strands and the bridges are angularly arranged, and in assembling the structure, the strands and bridges are so arranged that they slope inwardly toward the insulation, as indicated in 105 Figure 3, for a purpose to be described.

110 The metallic reinforcing sheets are preferably secured to the insulation 10 in spaced relation thereto, as shown in Figure 3, although other means to be described may be employed. Referring to Figure 3 the numeral 14 designates a transverse shank having a deformed central portion 15 mounted in the body of the heat insulating material 10 to 115 mechanically and frictionally engage the same to hold it in the desired spaced relation to the metal. In the present instance the deformed portion of the shank is illustrated as being in the form of threads. The connecting shanks 14 are arranged at spaced intervals 120 throughout the area of the sheet 10, and the outer ends of the shanks are spotwelded to certain of the bridges 13. In this connection, it will be noted that the complete sheets of 125 metal at opposite sides of the structure are preferably arranged in registration so that each end of each shank 14 may be welded to bridge portions of the metal. The completed structure is adapted to receive opposite layers 130

of cementitious material 16, as illustrated in Figure 3.

In Figures 4, 5 and 6 of the drawings, a modified form of structure is employed. In such form, reinforcing metal 17 is employed at opposite sides of a sheet of insulating material 18', substantially in the manner previously described. The metal 17 includes strands 18 connected at their ends by solid bridges 19, and certain of the bridges 20 are stamped from one side of the plane of the sheet of metal, as illustrated in Figures 4 and 6. The stamping of the bridges 20 is accomplished without distorting the body of the sheet, the four strands 18 diverging from each bridge 20 being stretched to permit the offsetting of the bridge and they form a rigid four point bracing element to maintain the position and integrity of the reinforcing sheets when joined as shown. In this connection it will be noted that the bridges 20 and the diverging strands which have been stretched in the manner referred to, are not distorted from their usual angular position, and accordingly each bridge 20 contacts with the sheet of insulating material 10 only at its inner edge.

It will be apparent that the greater portions of the sheets of metal 17 lie in planes spaced from and parallel to the insulating material 10, each bridge 20 being stamped from the plane of the sheet in the same manner and the same distance so as to secure the parallel relationship referred to. Substantially U-shaped metal clips 21 are employed for securing the bridges 20 to the insulating material 10. These clips are preferably pointed at both ends as at 22, (see Figure 4). The body of each clip extends around a bridge 20 at one side, then through the insulating material 10, and the points are turned around a bridge 20 at the other side and then into the insulating sheet 10. The completed structural unit illustrated in Figures 4, 5 and 6 also is adapted to receive a layer or layers of cementitious material 23.

The form of the invention illustrated in Figure 7 is particularly adapted for certain uses such as in floors, roofs, and the like wherein it is essential that one side of the finished structure be greatly reinforced to increase the compression strength while the concrete is being placed and then taking the tensile strains after the structure is completed. In this form of the invention, a sheet of insulating material 24 is employed which is similar to the insulating material previously described. A metallic reinforcing structure 25 is arranged at one side of the sheet, and is similar in form to the reinforcing structures previously referred to. At the opposite side of the structure a second metallic reinforcing unit 26 is employed, which is arranged a substantial distance from the adjacent surface of the insulating material 24.

A different form of means for securing the reinforcing units to the insulating sheet also is illustrated, but the securing means previously described may be employed if desired. This is particularly true of the securing means 14 70 illustrated in Figure 3.

Referring to Figure 7 it will be noted that the securing means comprises a metallic clip 27 which, when the structure is assembled, includes an intermediate straight shank portion 28. One end of the clip is turned about a bridge of the reinforcement 25, as indicated at 29, and the extremity of the clip lies against the adjacent surface of the sheet 24 as indicated at 30. The opposite end of the clip is turned as at 31 about a bridge of the reinforcement 26 to form a tie and to prevent outward movement thereof. The last named end of the clip then curves as at 32, and has its extremity turned as at 33 and lying against the adjacent surface of the sheet 24. It will be apparent that the clip is adapted to hold the elements of the semi-finished unit in proper position with respect to each other and it is understood that bending of the metal clips may be done in any manner to accomplish these results. Cementitious material 34 also is adapted to be applied against opposite sides of the unit illustrated in Figure 7.

Referring to Figure 2, it will be noted that a novel means is employed for bonding a number of the structural units into a completed wall or similar structure. It will be noted from Figures 1 and 2 that each metallic reinforcing unit projects beyond the sheet of insulating material, and as previously described, both the strands and the bridges of the metal are inclined. It has been found that if the metal is extended beyond the sheet 10 to the extent of one-half the width and depth of the outermost diamonds of the metal, or to the extent of one complete diamond when joined together, such extending portions will nest within the corresponding portions of the adjacent sheets as indicated at 35 in Figure 2, and there will be no perceptible bulge or projection at the overlapping portions of the metal. Accordingly, when the cementitious material is applied, such material will efficiently bond together the reinforcing units of adjacent sheets, thus forming a wall or similar structure having all the advantages of a unit construction.

The form of the invention illustrated in Figures 8 and 9 is employed where heat and sound insulation is of no importance, and it is desired to provide a completely bonded metal reinforced concrete structure of great strength and minimum thickness. Referring to these figures, it will be noted that a central body 36 is employed in the form of metallic lathing, or any other suitable openwork metallic structure. The lathing is flanked on opposite sides by sheets of expanded reinforcing metal 37, and since such reinforcing ele-

ments are similar to the corresponding elements illustrated in Figures 5 and 6, they need not be referred to in detail. As illustrated, certain of the bridges of the reinforcing sheets 37 are offset inwardly as at 38 to contact with the body 36, and the offset bridges are preferably connected to the body 36 by suitable connecting wires 39. It will be apparent however, that any other suitable connecting means may be employed.

The operation of the building units will be apparent from the foregoing description. As previously stated, the problems involved in building insulated reinforced walls on the job are such as to render the work tedious and so expensive as to be prohibitive. According to the present invention, the sheets of reinforcing material are arranged against opposite sides of the sheet of insulating material 20 and are secured thereto and therethrough according to either of the various means described. Thus the sheets of reinforcing material and the insulating material are secured in proper relative positions according to the character of the structure to be erected, and are held in such positions during handling, shipment and erection. In this connection, particular attention is invited to the fact that the metallic structure at each side and edge of the unit effectually prevents injury to the insulating sheet, and this is particularly important when cork is employed as the heat insulating means, as is desirable because of the superior insulating qualities of such material.

The units are placed in proper position according to their use. If the units are to be employed for forming partitions, for example, they are vertically arranged as illustrated, and cement or other cementitious material applied against the opposite sides thereof. In the form of the invention illustrated in Figures 1 and 3, each entire metallic structure is spaced from and arranged parallel to the layer of insulating material, and thus except merely for the shanks 14, all of the strands and bridges of each metallic sheet will be wholly embedded in the cementitious material, which is adapted to entirely fill the spaces between the reinforcing metal and the insulating material, and to be built up outwardly of the building unit to any desired thickness according to the use to which the structure is to be put.

In connection with the application of the cementitious material, attention is invited to the fact that the units are arranged in vertical position when used for partitions, walls and the like, and under such conditions, the inclination of the strands 12 and bridges 13 is downwardly and inwardly toward the sheet 10 and thus the plastic or semifluid cementitious material is assisted in its inward movement toward the sheet 10 to entirely fill the spaces between the metal and the sheet of in-

sulating material and the plastic material will be supported until it hardens. The overlapping of the edge portions of the metal of adjacent sheets causes such overlapped portions to be wholly embedded in and bonded with the concrete or other cementitious material, and thus the finished structure possesses substantially the same structural and tensile strength as does a unitary construction.

The operation of the form of the invention illustrated in Figures 4, 5 and 6 is substantially the same as in the form previously described, and need not be referred to in detail. It will be noted however, that only the lower edge portion of each bridge 20 contacts with the sheet of insulating material, and thus the metallic portion of the structure will be almost wholly surrounded by and embedded in the cementitious material applied against opposite sides of the unit.

The form of the invention illustrated in Figure 7 is particularly adapted for use in a floor slab or other unit which must stand transverse strains applied from one side of the structure. For example, if the structure illustrated is employed in a floor slab, the metal reinforcing 26 is arranged at the bottom of the structure and its spacing from the other elements of the structure greatly adds to the inherent strength of the floor.

It will be apparent that metal of any desired gauge may be employed, and it is preferred to employ, in most instances, the heavier gauges of metal with large mesh openings due to the economy of its use and the increased tensile strength of the resulting structure. It also will be apparent that metal of different sized mesh may be employed at opposite sides of a unit. For example, the structure illustrated in Figure 7 may be provided with a relatively light metallic element 25 and relatively heavy metal 26.

It will be apparent that the units described form an integral part of the insulated building structure and when initially placed in position they act as forms against which the cementitious material may be applied. The finished structure possesses high efficiency as both heat and sound insulating means, and also possesses a very high degree of tensile and compression strength as well as being fireproof and sanitary.

As previously stated the structure is readily adapted for use in forming various building structures such as floors, walls, partitions, etc. It also will be apparent that the structure lends itself readily for use in connection with stucco walls, in which case the outer face of the structure is adapted to receive concrete to the desired thickness, which is permitted to harden, whereupon it forms a base to which mortar may be applied.

The inventive idea embodied in the structure illustrated in Figures 8 and 9 is the same as in the forms previously described, except that it is adapted for use in forming a completely bonded metal reinforced construction where heat and sound insulation is of no importance. The provision of the central body 36 and the spaced reinforcing elements 37 forms a semifinished unit of substantial thickness, and when concrete or other cementitious material is applied to opposite sides of the structure, the material bonds completely through the meshes of the central body 36, as well as through the meshes of the reinforcing elements 37. It has been found that great tensile and compression strength may be provided in proportion to the thickness of the resulting wall or other construction.

It is to be understood that the forms of my invention herewith shown and described are to be taken as preferred examples of the same and that various changes in the shape, size, and arrangement of parts may be resorted to without departing from the spirit of the invention or the scope of the subjoined claims.

I claim:

1. A building unit comprising a central body, a metallic reinforcing element arranged at each side of said body, and fastening means each securing said elements to each other through said body and for spacing said elements from said body throughout the greater portion of their areas, said securing means being arranged at spaced points to prevent relative movement between said body and said reinforcing elements.

2. A building unit comprising a central body, an open-work substantially rigid metallic reinforcing element arranged adjacent each side of said body and at least coextensive therewith, and means arranged at a plurality of spaced points for substantially positively securing said elements to each other and to said body and operative for spacing said elements from said body throughout the greater portion of their areas.

3. A building unit comprising a central body, a relatively rigid expanded metal reinforcing element arranged adjacent each side of said body and substantially coextensive therewith, each reinforcing element including strands and bridges all inclined in the same direction toward said body, and means extending through said body at a plurality of spaced points for substantially positively attaching said reinforcing elements to each other and to said body and for supporting said elements with the greater portions thereof arranged in spaced parallel relationship to said body.

4. A building unit comprising a body of sound and heat insulating material of relatively low structural strength, a relatively rigid expanded metal reinforcing element ar-

ranged adjacent one side of said body and substantially coextensive therewith, and a plurality of spaced attaching elements having portions extending entirely through and embedded in said body and other portions positively connected to said reinforcing element to substantially rigidly support the latter in spaced parallel relation to said body.

5. A building unit comprising a body of sound and heat insulating material of relatively low structural strength, a relatively rigid open-work metallic reinforcing element arranged on each side of said body, and an attaching element arranged at each of a plurality of spaced points, said attaching elements extending entirely through said body and positively connecting said reinforcing elements to each other and to said body.

6. A building unit comprising a body and a relatively rigid expanded metal reinforcing element connected to said body at spaced points in parallel spaced relation to said body, said reinforcing element having angularly arranged strands and bridges and projecting beyond at least one edge of said body whereby the projecting portions of the reinforcing element of an adjacent unit are adapted to interlock therewith with the overlapping strands and bridges in flat contact with each other.

7. A building unit comprising a central body, a relatively rigid expanded metal reinforcing element of relatively large mesh arranged adjacent each side of said body, and means passing through said body for attaching said reinforcing elements to each other and to said body at a plurality of spaced points to support said elements with the greater portions thereof arranged in spaced parallel relation to said body, said elements including angularly arranged strands and bridges projecting beyond at least one edge of said body to overlap the projecting portions of the reinforcing elements of an adjacent unit having similarly arranged strands and bridges whereby the overlapping strands and bridges will coincide and lie flat against each other.

8. A building unit comprising a body of sound and heat insulating material of relatively low structural strength, a relatively rigid open-work metallic reinforcing element arranged on each side of said body, and a plurality of attaching elements arranged at spaced points throughout the area of said body and extending entirely therethrough, each attaching element having a deformed portion intermediate its ends embedded in said body and having its ends positively secured respectively to said reinforcing elements.

9. A building unit comprising a body of sound and heat insulating material of relatively low structural strength, a relatively rigid expanded metal reinforcing element ar-

ranged adjacent each side of said body and each having portions offset inwardly toward and contacting with said body to space the greater portions of the areas of said reinforcing elements from said body, and a plurality of fastening elements arranged at spaced points throughout said body and extending entirely therethrough, the end portions of said elements being looped around the inwardly offset portions of the respective reinforcing elements for securing them to said body.

10. A building unit comprising a body of sound and heat insulating material of relatively low structural strength, a relatively rigid expanded metal reinforcing element arranged adjacent each side of said body and having the greater portion of their areas arranged in spaced parallel relationship thereto, and a plurality of fastening elements arranged at spaced points throughout said body and extending entirely therethrough, each of said fastening elements comprising a metallic shank having its intermediate portion projecting through said body, the end portions of said shanks being looped around portions of the respective reinforcing elements and having substantial portions of their extremities extending along and contacting with opposite faces of said body for substantially positively supporting said reinforcing elements with respect to said body in said parallel relationship.

In testimony whereof I affix my signature.

JOHN H. MAGEE.
